UNITED STATES PATENT OFFICE.

JOHN E. PACKARD, OF CHICAGO, ILLINOIS, ASSIGNOR TO MULTI-VENDING COMPANY, OF PIERRE, SOUTH DAKOTA, A CORPORATION OF SOUTH DAKOTA.

DELIVERY MECHANISM FOR VENDING-MACHINES.

No. 833,384.

Specification of Letters Patent.

Patented Oct. 16, 1906.

Application filed April 18, 1904. Serial No. 203,798.

To all whom it may concern:

Be it known that I, JOHN E. PACKARD, a citizen of the United States, residing at Chicago, in the county of Cook and State of Illinois, have invented certain new and useful Improvements in Delivery Mechanism for Vending-Machines, of which the following is a specification.

The invention relates to the support carrying the roller for discharging the vendable article and for centering the revoluble receptacle carrying the vendable articles and to the means for giving the roller the requisite yield and return to perform its office.

The objects of the invention are to furnish a swinging and yieldable support for the discharging and centering roller, by which the roller will be positively moved to act as a discharger and will be maintained in an elevated position to act as a stop and centering device without creating an undue amount of friction in its use; to cause the roller to be returned under conditions that will not create any jar or recoil; to furnish a support for the roller formed in two sections, one section mounted on a rock-shaft and the other section mounted on a rock-shaft or rod carried by the first section and free to vibrate with the rock-shaft or rod, and to improve generally the construction and operation of the several devices employed in the making of the apparatus as a whole.

The invention consists in the features of construction and combinations of parts herein-after described and claimed.

In the drawings only the operative mechanism relating to the control and positioning of the revoluble carrier or receptacle for the articles are shown, as the invention relates particularly to this mechanism.

Figure 1 is a side elevation of the mechanism of the invention mounted on a plate for attachment within the case of the vending-machine; Fig. 2, a top or plan view of the mechanism shown in Fig. 1 with a coin receiver or cradle added; Fig. 3, a rear elevation; Fig. 4, a side elevation showing only the support or cradle for the roller and the parts directly coöperating therewith; and Fig. 5, a side elevation of the discharging mechanism in connection with a package-carrier, which latter is shown in sectional elevation.

The mechanism of the invention as a

whole in the arrangement shown is mounted on a base-plate A, which can be attached to the bottom of the casing of the machine by screws passing through holes a in the base-plate or in any other suitable manner. The plate A has mounted thereon a rock-shaft B, which shaft is supported in bearings b, projecting upwardly from a plate b', riveted or otherwise secured to the base-plate, so that the rock-shaft has a firm bearing and is free to be rocked.

The rock-shaft has secured thereto a pair of standards or uprights C, each standard or upright having at its lower end a collar or hub by means of which and a suitable set-screw or otherwise it is fixedly attached to the rock-shaft. The upper end of each standard or upright C has a socket or bearing c', in which is mounted a shaft or rod D, the ends of the shaft in the arrangement shown being upset to form heads d, by which the shaft or rod D is held in its bearings against end movement. Each end of the rock-shaft or rod D has fixed thereto the side bars e of a yoke-frame E, and, as shown, the fixed end of each side bar e is located between the bearing e' for the shaft or rod D and the upset end d of such shaft or rod. The yoke-frame E consists of side bars e and an end bar e' at the free end of the frame, and, as shown, in order to furnish additional strength each side bar e has a flange or right-angle piece e'', which, however, is not a necessity otherwise than for additional strength.

A stirrup F is attached to the end bar e' of the yoke-frame, and this stirrup consists of side bars f and an end bar f', and each side bar has a turned end or flange f'', by means of which and suitable rivets or otherwise the stirrup is attached to the end bar e' of the frame, and, as shown, at the free end of the yoke-frame on each side bar e is secured a plate f'', having a depending ear f''' with a hole, in which ear is mounted an apron. (Not shown.) The ejector and centering roller G is located in the stirrup F, and this roller G has at each end a journal-pin g, one of the journal-pins entering an eye or bearing g' on the cross-bar f' of the stirrup and the other journal-pin g entering a bearing or eye g'' on the cross-bar e' of the yoke-frame.

The carriage formed of the yoke-frame E and stirrup F for the ejector G is to be yield-

ably supported, so that it will yield when required and will be returned to its engaging position when required. This carriage or support for the ejector in the construction shown is yieldably supported against dropping too far and also held in operative position for the ejector by a flat spring H, one end of which is attached to a stud or pin h, projecting out from an upright 5 or standard C, and the other end of which is attached to a stud or pin h', projecting out from a side bar e of the yoke-frame. The body of the spring passes from the stud h to the stud h', forward of a pin h², so that the 10 upper portion of the body of the spring has an upward curve by which it has a lifting action on the swinging yoke-frame, by which the frame will be pressed constantly upward to the limit of the spring, holding the roller 15 normally raised, and at the same time the yield of the spring is sufficient to allow the roller to be forced down in use. It will be seen by this arrangement that the spring H furnishes a yieldable support for the ejector 20 through its carriage, and this support from the spring is constant, as the spring travels with the uprights or standards and with the yoke-frame, and at the same time the spring is free to yield as the ejector is forced downward, giving the necessary resistance to the 25 spring to return the ejector to normal position, when the depressing force is removed from the engagement therewith. It will further be seen that the carriage for the 30 ejector is free to rise and fall with the rock-shaft or rod D as a pivot, and that the rock-shaft or rod D has a fixed relation with the rock-shaft B for supporting the standards or uprights C, which furnishes a double pivot 35 for the carriage, one through the rock of the shaft B, which carries the uprights or standards to and fro, and another through the rock-shaft or rod D, which allows the yoke-frame to rise and fall, and that both movements are independent of each other, but at 40 the same time the rock of the shaft or rod D is dependent on the rock of the shaft B in moving the standards or uprights. This arrangement gives a positive rock by which 45 the ejector is advanced and receded and a positive swing by which the ejector is free to rise and fall, and these two movements of the ejector render the operation of the ejector positive and reliable, one rock movement 50 operating the ejector to discharge the article to be vended and the other rock movement insuring the release and engagement of the ejector with the carrier of the vendable articles. 55

60 The return of the rock-shaft B to swing the uprights or standards C forwardly at their upper ends should be controlled so as to prevent a too quick return of the ejector or discharge-roller to its normal position.

65 This slow return or back rock of the shaft B

is obtained by a lever I, having at its lower end a socket i, by means of which the lever is fixedly attached to the end of the rock-shaft B by a cross-pin i' passing through the socket i and the end of the shaft. At the 70 front of the plate A is a standard or post J, having at its lower end a flange or foot j, by means of which it is fixedly attached to the base-plate. This standard J and the lever I are in line with each other. The upper end j' 75 of the standard J has attached thereto by a pin or pivot k' the stem k of a plunger K of a dash-pot, the movable section K' of which is attached by ears k² and a pin or pivot k³ to the upper end of the lever I, so that with 80 the outward movement of the upper end of the lever I the cylinder or movable section K' of the dash-pot will travel outwardly on the plunger or fixed section of the dash-pot.

The lever I is returned by a coil-spring J', 85 one end of which is hooked into one of a series of holes i² in the lever and the other one of which is hooked into one of a series of holes j² in the post, the holes serving as a means for adjusting the spring so as to give a 90 greater or less force in action. This coil-spring J' is expanded with the backward movement of the lever I and placed under a strain sufficient to exert a force to return the lever to normal position, and with the return 95 of the lever I to normal position the action of the dash-pot prevents a too rapid or quick return of the lever to its normal position and preventing the rock-shaft B, and with it the carriage of the ejector or roller-discharger, 100 being returned too quickly, thus preventing a jar on the return movement of the ejector or roller-discharger.

The discharging mechanism is located in 105 juxtaposition to a package-carrier, and the package-carrier, as shown, has a shaft L mounted at its lower end in a step or bearing l and having at its upper end a collar l', and from the upper end of the shaft a brace or support L' extends and is connected at its 110 lower end to the base A of the machine, and, as shown, the brace is held in position between the collar l' and a pin l², passing through the end of the shaft, thus giving the shaft a firm bearing at both its upper and 115 lower ends. A package-carrier M is fixedly connected with the shaft and consists of a plurality of receptacles m, each receptacle adapted to carry the articles to be vended. A plate N, having a hub n, is attached to the 120 shaft by a cross-pin n', and this plate has secured to its under face a metal or other ring N', having ears or flanges n² and n³ for the attachment of the receptacles or compartments m to the support. A plate or 125 disk O, having a hub o, is attached to the shaft by a cross-pin o', and this disk has secured thereto a ring of metal or other material O', having ears o² for attachment of the walls of the receptacles or compartments to 130

- the ring. The disk or plate N and the disk or plate O, in connection with the rings N' and O', support the package-carrier as a whole so as to revolve with the shaft. Each receptacle or compartment *m* has a plate P, beneath which is a discharge mouth or opening P' for the articles from the receptacle or compartment, and attached to the bottom of the package-carrier is a track *p*, having straight faces and curved faces, the curved faces forming depressions *p'* to receive the periphery of the discharging-roller *G* and lock and hold the package-carrier in direct line for a compartment thereof to be in alignment with the discharge-roller, so that the advance of the discharge-roller will remove an article from the compartment or receptacle to be delivered to the purchaser. The package-carrier has a circumferential wall or flange Q, attached to the carrier by supports or braces *q* and which furnishes a grab by means of which the purchaser can revolve the package-carrier into position for the desired receptacle or compartment *m* to be in line with the discharge-roller, so that on depositing the proper coin the discharge-roller can be advanced to remove the package or article from the compartment for delivery to the purchaser.
- The use of the package-carrier in connection with the discharge-roller will be readily understood from the foregoing description and the description of the operation of the discharge-roller.
- The operation, briefly, is as follows: The ejector or discharge-roller *G* is held in its normally raised position by the action of the spring *H*, and when in its raised position on the backward movement of the standards or uprights *C* the carriage in which the ejector or discharge-roller is mounted will be carried rearwardly for the ejector to act and discharge the lowermost one of the articles. The throw of the standards *C* at their upper end is sufficient to move the ejecting-roller *G* the distance to discharge a package from the commodity-carrier, and the return movement of the standards *C* carries the ejecting-roller *G* into a position to engage with a new package and discharge such package with the rearward movement of the upper ends of the standards. The standards swing with the shaft *B*, and the frame also swings on or with the cross-rod *D*, giving the carriage, which supports the ejector or roller *G*, a double oscillation, thus guarding effectually against rigidity of movement in operating the ejector or ejecting-roller both in its advance and in its return movements.
- The drawings, Fig. 2, show a plan view of a coin receiver or cradle and of a plunger to engage the coin in the receiver or cradle and rock the shaft *B* to swing the frame or support of the ejector or ejecting-roller. The coin-receiver *L* has on opposite sides of its
- interior spiral ribs *l*, down which the deposited coin travels vertically edgewise and is turned crosswise of its entered position, so as to stand in such relation with the plunger *K* as to have the end of the plunger engage 70 the face of the coin when the plunger is advanced. The plunger *K* is carried by an arm *k*, mounted at its lower end loosely on the rock-shaft, and the plunger is advanced and receded by swinging the arm *k* on the rock-shaft *B* through any suitable mechanism. The receiver or cradle has through its wall at the top a slot *l'* for entering the coin into the spiral pathway to descend therein. A detail construction and illustration of the coin-controlled mechanism is not deemed necessary, as the present invention is confined to the delivery mechanism, and any construction of coin-controlled mechanism that will rock the shaft *B* and swing the standards *C* 85 can be employed.
- What I regard as new, and desire to secure by Letters Patent, is—
1. In a delivery mechanism for vending-machines, the combination of a rock-shaft, 90 upwardly-extending standards fixedly attached at their lower ends to the rock-shaft to swing horizontally at their upper ends, a rocking cross-rod mounted in the upper end of the standards, a horizontal frame fixedly 95 attached at its inner end to the rocking rod a yieldable support carrying the horizontal frame under tension to rise and fall vertically at its outer end, and an ejector carried by the frame at its outer end, substantially 100 as described.
  2. In a delivery mechanism for vending-machines, the combination of a rock-shaft, upwardly-extending standards fixedly attached at their lower ends to the rock-shaft 105 to swing horizontally at their upper ends, a rocking cross-rod mounted in the upper end of the standards, a spring-supported horizontal frame fixedly attached at its inner end to the rocking rod to rise and fall vertically at 110 its outer end, and an ejector carried by the frame at its outer end, substantially as described.
  3. In a delivery mechanism for vending-machines, the combination of a rock-shaft, 115 an ejector supported on the rock-shaft and having a horizontal movement derived from the rock-shaft, an upwardly-extending lever fixedly attached at its lower end to the rock-shaft, a fixed support, a spring located between the lever and the fixed support and operating to return the lever to normal position, and a dash-pot, one section of which is attached to the fixed support and the other section of which is attached to the lever, for 120 the dash-pot to resist the action of the spring and cause a slow return of the ejector, substantially as described.
  4. In a delivery mechanism for vending-machines, the combination of a rock-shaft, a 130

carriage supported from the rock-shaft and having a horizontal movement derived from the rock-shaft, a package-ejector on the carriage, an upwardly-extending lever fixedly attached at its lower end to the rock-shaft, a fixed support, a spring located between the lever and the fixed support and operating to return the lever to normal position, and a dash-pot, one section of which is attached to the fixed support and the other section of which is attached to the lever, for the dash-pot to resist the action of the spring and cause a slow return of the ejector, substantially as described.

15. 5. In a delivery mechanism for vending-machines, the combination of a rock-shaft, upwardly-extending standards fixedly attached at their lower ends to the rock-shaft to swing horizontally at their upper ends, a rocking cross-rod mounted in the upper end

of the standards, a frame fixedly attached at its inner end to the rocking cross-rod to rise and fall vertically at its outer end, an ejector carried by the frame at its outer end, an upwardly-extending lever fixedly attached at its lower end to the rock-shaft, a fixed support, a spring located between the lever and the fixed support and operating to return the lever to normal position, and a dash-pot, one section of which is attached to the fixed support and the other section of which is attached to the lever, for the dash-pot to resist the action of the spring and cause a slow return of the ejector, substantially as described. 25 30
